UNITED STATES PATENT OFFICE.

ARTHUR F. BROWN, OF SOMERVILLE, MASSACHUSETTS.

MOP.

No. 911,199.

Specification of Letters Patent.

Patented Feb. 2, 1909.

Application filed April 6, 1908. Serial No. 425,348.

To all whom it may concern:

Be it known that I, ARTHUR F. BROWN, a citizen of the United States, residing at Somerville, in the county of Middlesex and State 5 of Massachusetts, have invented a new and useful Mop, of which the following is a specification.

This invention relates to a household implement which is more particularly designed 10 for wiping dust or moisture from a floor, although it is useful for rubbing and polishing floors and cleaning walls, ceilings and windows.

The object of the invention is to provide 15 a very simple, cheap and efficient implement which is light in weight and can be manipulated by anyone, which is so constructed that cleaning, dusting or polishing material of any suitable nature, can be easily applied 20 and its position instantly changed when a part becomes soiled or wet, so that a clean or dry portion is always available, which wiping or polishing material can be quickly removed, cleaned and replaced whenever de- 25 sired.

The embodiment of the invention illustrated has a handle by means of which the implement may be manipulated, provided 30 with a head about which is stretched a web or apron that is loosely retained in position by a cord which is held under tension by suitable means, for the purpose of keeping the apron taut, which apron is provided 35 with clips by means of which a wiping, polishing, drying or scrubbing cloth can be quickly attached to or removed from the apron.

Figure 1 of the accompanying drawings shows a front view of the implement. Fig. 40 2 shows an edge view. Fig. 3 shows a view of a portion of the handle and the head on larger scale. Fig. 4 shows a section of the handle and the head with a portion of the apron and wiping cloth passing around the head.

The handle 1 is preferably made of wood although it can be formed of other material, such as metallic tubing if desired. A button 50 2 of rubber is desirably fastened to the upper end of the handle, and at the lower end the handle is connected by a fitting 3 with a head 4 that is preferably made of wood and provided on its edges with strips 55 of rubber, felt or the like. This head could of course be formed of metal if de-

sired, and its upper face is preferably flat, while its lower face is curved in such manner that quite a portion will always remain on the surface to be wiped regardless of variations of the inclination of the handle. 60 The front edge of the head is desirably slightly curved and a groove 6 is made in the front edge and under surface of the head.

The apron 7 which is drawn around the head is desirably made of one or more strips 65 of canvas, duck or heavy textile fabric, although it can be made of rubber. The ends of the apron are attached to cross bars 8 for the purpose of keeping it flat, and these bars are connected by a cord 9 that is led 70 through a slot 10 in the handle. A sleeve 11 that is loose on the handle adjacent to the slot and is pressed upwardly by a spring 12 that thrusts against a collar 13 fixed to the handle keeps the cord taut and the apron 75 stretched. A cord or seam 14 is arranged longitudinally of the center of the apron to form a rib on the inside, and this rib by engagement with the groove 6 aids in keeping the apron properly on the head when it is 80 drawn back and forth.

Clips 15 of any desired form may be fastened to the cross bars for the purpose of temporarily holding the wiping cloth 16 which may be flannel, felt or similar textile 85 fabric which has considerable nap, or has an affinity for dust and moisture, and which is desirably applied in several laps so it may be refolded to provide a clean surface before necessitating washing. After the desired 90 wiping cloth is attached, the cord is preferably pulled so that the front end of the apron is drawn near the head. The device may then be used for wiping moisture or 95 dust from a floor, wall, ceiling, or window, and when one section becomes soiled or full of dirt or moisture, the front end of the apron can be pulled upwardly so as to draw a fresh section of the wiping cloth beneath the head, and thus a clean or dry part of 100 the wiping cloth is always available for continuing the work. When dust has been removed from a floor or other surface the apron can be shaken out of a window for removing the dust from the nap of the wiping cloth, or the cloth can be removed from the clips and shaken or washed, as desired. 105

This implement is very cheap to manufacture, is very light in weight so that it can be conveniently used by anyone without 110

effort and is so shaped that it can be manipulated on a floor beneath a bed or other articles of furniture and close to walls or other surfaces and in corners. Any kind 5 of rubbing cloth can be quickly attached to the apron and a fresh section is always available for use.

The invention claimed is:

1. A mop having a handle, a head attached to the handle, an apron movable about the head and means connecting the ends of the apron with the handle for holding the apron in place, substantially as specified.
- 10 2. A mop having a handle, a head attached to the handle, an apron movable about the head, means connecting the ends of the apron with the handle, and means for securing a wiping cloth to the apron, substantially as specified.
- 15 3. A mop having a handle, a head attached to the handle, a movable apron passing around the head and extending along the handle, means connecting the ends of the apron for holding the apron taut, and means for securing a wiping cloth to the apron, substantially as specified.
- 20 4. A mop having a handle, an apron movable longitudinally with relation to the handle, a cord connecting the ends of the apron and means for holding the cord taut

and the apron stretched, substantially as specified.

5. A mop having a handle, a head attached to the handle, a flexible apron movable longitudinally of the handle about the head, a cord connecting the ends of the apron, and a spring for keeping the cord taut and the apron stretched, substantially as specified.

10 6. A mop having a handle, an apron movable longitudinally with relation to the handle, a cord extending through a slot in the handle and connected with the ends of the apron and clips mounted on the apron for the temporary attachment of a wiping cloth, substantially as specified.

15 7. A mop having a handle, a head attached to the handle, an apron movable longitudinally of the handle around the head, a cord extending through a slot in the handle and attached to the ends of the apron, a sleeve movable on the handle and forming a bearing for the cord, a spring thrusting the sleeve against the cord, a collar 50 for holding the spring, clips attached to the apron and a wiping cloth held by the clips, substantially as specified.
